[57] CLAIM

The ornamental design for a grip for holding a gas pump nozzle in the open position, as shown.

DESCRIPTION

FIG. 1 is a front perspective view of the grip for holding a gas pump nozzle in the open position showing my new design;

FIG. 2 is a top plan view thereof;

FIG. 3 is a front elevational view thereof;

FIG. 4 is a bottom plan view thereof;

FIG. 5 is a left side elevational view thereof;

FIG. 6 is a right side elevational view thereof; and

FIG. 7 is a back elevational view thereof.
